United States Patent Office.

R. M. THOMPSON, OF COSHOCOTON, OHIO.

Letters Patent No. 77,678, dated May 5, 1868.

IMPROVED LIFTING-JACK.

The Schedule referred to in these Letters Patent and making part of the same.

TO ALL WHOM IT MAY CONCERN:

Be it known that I, R. M. THOMPSON, of Coshocton, in the county of Coshocton, and State of Ohio, have invented a new and improved Lifting-Jack; and I do hereby declare that the following is a full and exact description of the same, reference being had to the accompanying drawings, and to the letters of reference marked thereon.

This invention relates to an improved lifting-jack, the novelty of which consists principally in a pivoted and weighted stirrup-iron, which swings under the lifting-bar when the load is raised, and supports the weight; also, in certain other devices whereby this arrangement is made effective, as will be fully described hereinafter.

In the drawings, A represents a base-block of any suitable size and shape, from which rises the standard B.

C represents a lever provided with a slot, *a*, through which the standard B passes, which is pivoted to the latter at the point *x*.

D represents a guard-piece, constructed as shown, and attached in any proper manner to the upper part of the standard B.

E represents an iron rod, resting in a socket in the lever C, and pivoted thereto, over which is placed the hollow box F.

e e represent notches in the rod E, which correspond in position with the hole *f* in the box F, so that when the pin *f* is inserted into the hole *f*, it rests in one of these notches *e e*. By means of this latter arrangement the box is shifted to any desired height within the range of the jack.

G represents a stirrup-iron pivoted to the lever C, as shown, which is so constructed that its lower part is much more weighty than its upper, the effect of which arrangement is that when the long arm of the lever C is depressed, the stirrup-iron, by its own weight, assumes a perpendicular position under the end of the short arm, and, the pressure being relaxed, the whole weight is borne by it.

g represents one side of the stirrup-iron, which extends above its pivot-point, to which the link *g* is attached, connecting with which latter is the rod *g*, terminating in the handle *g*.

It will be observed that the under part of the stirrup-iron, and also the corresponding part of the base, are inclined; this construction being for the purpose of permitting the iron to come readily to place when the lever is depressed.

From this description, the operation of my jack will be readily understood.

The lifting-bar having been first adjusted, by means of the pin *f* having been placed in the proper notch of the rod E, the latter having been moved up or down to the proper point for this purpose, the jack is placed under the axle or other matter to be raised. The long arm of the lever C being depressed, the short arm is consequently elevated, and with it the lifting-bar. At the same time the stirrup-iron, by its own weight, assumes a perpendicular position directly under the lifting-bar, and the lever C being released, all the weight is borne by it.

When it is desired to let down the jack, the lever C should be held, when the handle *g* being pulled, the stirrup-iron is thrown up and the load may be then gradually eased down. By this simple arrangement the weight of the load, when the jack is in operation, rests in a direct line upon the lifting-bar and the stirrup-iron, and all the other parts are relieved entirely from the strain.

Having thus fully described my invention, what I claim as new, and desire to secure by Letters Patent, is—

1. The lever C and standard B, in combination with stirrup-iron G, substantially as described.
2. The base, A, standard B, lever C, guard-piece D, rod E, box F, and stirrup-iron G, the whole being combined and arranged substantially as described.

This specification signed and witnessed, this third day of March, 1868.

R. M. THOMPSON.
